Primary Examiner — Elizabeth A. Albert(74) *Attorney, Agent, or Firm* — Mark M. Friedman(57) **CLAIM**

The ornamental design for a pen, as shown and described.

DESCRIPTION

FIG. 1 is a perspective view of the pen;
 FIG. 2 is a front elevational view of the pen;
 FIG. 3 is a rear elevational view of the pen;
 FIG. 4 is a left side elevational view of the pen;
 FIG. 5 is a right side elevational view of the pen;
 FIG. 6 is a top plan view of the pen;
 FIG. 7 is a bottom plan view of the pen; and,
 FIG. 8 is an exploded perspective view of the pen.
 The broken lines in FIG. 6 are included to show a portion of
 the pen that forms no part of the claimed design.
